(57) **CLAIM**

The ornamental design for fence post, as shown and described.

DESCRIPTION

FIG. 1 is a perspective view showing the top, front and left side of the fence post.

FIG. 2 is a view showing the back of the fence post of the present invention.

FIG. 3 is an elevation view showing the top, bottom, left side and right side of the fence post of the present invention; and, FIG. 4 is an enlargement of area 4 of FIG. 2 of the fence post of the present invention.

In the drawings showing a length of the fence post, the fence post has been broken in the center indicating indefinite length.
